UNITED STATES PATENT OFFICE.

WALTER B. ALLEN, OF ATTLEBORO, MASSACHUSETTS.

SANITARY DRINKING DEVICE.

Application filed July 28, 1921. Serial No. 488,119.

To all whom it may concern:

Be it known that I, WALTER B. ALLEN, a citizen of the United States, residing at Attleboro, in the county of Bristol and State 5 of Massachusetts, have invented certain new and useful Improvements in Sanitary Drinking Devices, of which the following is a specification.

My invention relates to that type of sanitary drinking fountain commonly known as 10 a bubbler.

The essential objects of my invention are to insure a close and firm means of connection with the faucet; to effect such a discharge of the liquid as will produce a perfect bubbler; and to attain these ends in an inexpensive and readily portable structure.

To the above ends my invention consists in such parts and in such combinations of 20 parts as fall within the scope of the appended claim.

In the accompanying drawings which form a part of this specification,

Figure 1 is a side elevation of my novel 25 bubbler engaged with a faucet, the latter being shown in broken lines,

Figure 2, a vertical central section of the same,

Figure 3, a plan of the head, and

Figure 4, a plan of the baffle plate.

Like reference characters indicate like parts throughout the views.

In detail my device comprises a substantially U shaped pipe comprising a semicircular body portion 6 with a long vertical arm 7 upon one end, and a shorter vertical arm 8 upon the other end. A frusto conical plug 10 of rubber or other compressible material has a central passage 11 to admit therethrough the arm 8 with which it is frictionally engaged at a point at or near the arm terminal. Fast to the top of the arm 40 7 is a hollow slightly flattened circular head comprising an inclined or dished lower plate 45 or wall 13 fast to or integral with whose periphery is a convex top wall or plate 14 provided with a central star shaped opening

15. A horizontally disposed baffle plate 17 is mounted midway of the head with its periphery located at the junction of the converging upper and lower convex walls 14 and 13. The baffle plate or disk 17 has an annular series of holes or perforations 18 in its margin remote from its center.

My device is portable and the plug 10 is 50 insertable in faucets 20 of different diameters by virtue of its inclined shape. Its compressibility also contributes to the same end. The liquid traverses the pipe portions 8, 6, 55 and 7 and passes through the opening in the head plate 13 and impinges against the baffle plate 17. Thence the liquid passes through the perforations 18, and is guided by the inclined face of the plate 14 through the serrated opening 15. The points or serrations 22 of the opening 15 are an important factor in that they break up the stream resulting in converting the liquid stream into bubbler form.

While reference has been made to the 70 shape of the plug 10 as frusto conical it will be understood that this term is meant to include plugs having an oval or elliptical cross section as well as a circular cross section.

I claim:—

In a portable bubbler, a pipe comprising a curved body, and arms of different lengths upon the ends of the body parallel with each other, a plug upon the shorter arm, a hollow discharge head upon the longer arm comprising a convex bottom plate, a convex top plate fast at its periphery to the periphery of the bottom plate and provided with a noncircular central opening, and a horizontal baffle plate supported between the first two plates provided with an annular series of marginal holes the portion of said baffle plate opposite said opening being imperforate.

In testimony whereof I have affixed my signature.

WALTER B. ALLEN.
